C. D. PAGE.

Lime Kiln.

No. 10,510.

Patented Feb. 7, 1854.

UNITED STATES PATENT OFFICE.

CLARK D. PAGE, OF ROCHESTER, NEW YORK.

LIMEKILN.

Specification of Letters Patent No. 10,510, dated February 7, 1854.

To all whom it may concern:

Be it known that I, CLARK D. PAGE, of the city of Rochester, in the county of Monroe and State of New York, have invented certain new and useful Improvements in Limekilns, of which the following is a full, clear, and exact description, reference being had to the accompanying drawings, making part of this specification, in

10 which—

Figure 1 is an isometrical view; Figs. 2 and 3 are vertical sections taken in planes at right angles to each other; Fig. 4 is a horizontal section taken at the line A, a of 15 Fig. 2. Fig. 5, is a vertical section taken at the line B, b of Fig. 4.

The letters of reference refer to the same parts in the different figures wherever they occur.

20 In my improved kiln for burning lime stone the charge is placed in a vertical stack or cupola, to which the flame and gaseous products of combustion are admitted from suitable fire chambers.

25 The first part of my invention which relates to the form of the stack, consists in making that part of the stack which receives the flame directly from the surrounding fires, smallest, and then a short distance 30 above this, spreading it out to its greatest diameter.

The object of this peculiar form in connection with the location and arrangement of the fire chambers and flues, is, that the 35 flame and heat which enter at the smallest part of the stack may reach the center of the charge to burn that part of the charge, which in other kilns is very seldom effected.

The second part of my invention consists 40 in combining with the stack, and at the lower end thereof below the fire chambers, a cold air flue which performs the double purpose of cooling and dividing the lime as it descends, and before it is drawn out and 45 exposed to the action of atmospheric air. This cold air flue extends across, and divides the lower end of the stack into two parts. It is made of metal, receives cold air in front which passes through it, and by 50 rarefaction ascends, and escapes through a flue built in the wall.

In the accompanying drawings a represents the walls of the kiln, which must be built of suitable materials, and strength, 55 and inclosing the stack or cupola b, which extends vertically through the entire height.

This stack from the level of the fire chambers c, c, upward, for about five feet to d, is cylindrical or nearly so, at d it begins to spread, and enlarges up to the opening of 60 the gas flues e, e, say a distance of five feet from d, and thence upward to f, f. Within a short distance of the top it is gradually contracted, so as to be reduced to the same size as the level of the fire chambers. The 65 upper end at g is funnel shaped to facilitate the introduction of the charge.

There are two main fire chambers c, c, one on each side, arched over at the top, provided with a large grate in the usual 70 manner for burning, and an ash pit below. There is a door h above the grate for fuel and draft and one i below, for raking out coals and ashes from the ash pit. Two flues j, j, open directly from each of these 75 fire chambers into the stack for the passage of the flame, and four (more or less) small flues k, extend through the top arch to a chamber l over each fire place, in which chamber is placed a cylindrical or other 80 formed, steam boiler m, so that the gaseous products of combustion from the main fire places which do not escape to the stack with the flame through the flues j, j, will rise and circulate around the boiler to generate 85 steam, and thence pass out through flues e, e, and enter the charge in the stack at its greatest width, to aid in heating the stone as it is descending in the process of calcination. From each boiler a steam pipe n, extends up in the wall, and is bent inward 90 near the top to discharge a jet of steam into the charge of stone to facilitate the liberation of carbonic acid gas, and at the same time to improve the draft through the 95 charge.

By the side of each of the main fire chambers there is an auxiliary fire chamber o adapted to the burning of charcoal, and therefore provided with a grate, and ash 100 pit, being provided with doors in the usual manner. And from each of these auxiliary fire chambers one or two flues p, p, extend horizontally to, and enter the stack at or near the same level with the flues j, j. The 105 main fire places are charged with wood, and the auxiliary fire chambers with the coals produced in the main fire chambers.

The stack extends down from the level of the fire chambers to receive the calcined 110 lime. And at the bottom there is what I term a metallic saddle q on which the lime

rests and which divides it, one half going on each side, to be drawn out at the proper time through two passages r, r . This metallic saddle is hollow and receives cold air 5 through an aperture s , in front, and discharges it, through a flue t extending to, and through the top. In this way I cause a current of cold air to circulate through the inside of this saddle for the purpose of cooling the calcined lime as it descends, and before it is drawn out, and exposed to the direct action of atmospheric air, which, it is known, has the effect to slack lime when it is brought in contact with it at a high temperature. The charge of limestone is introduced at the top, and as it is calcined and drawn out at the bottom, the supply must be continued at top.

By the peculiar form of the stack in connection with the supply of flame and other products of combustion at the small part of the stack, I am enabled effectually to burn or calcine the central part of the charge. And by the introduction of the 25 current of cold air through what I term the

saddle I am enabled to bring down the temperature of the calcined lime, so that it can be drawn out without danger of being air slacked.

What I claim as my invention and desire 30 to secure by Letters Patent, is—

1. The form substantially as described, of the stack or cupola, in combination with the arrangement of flues from the fire chambers for the introduction of the products of 35 combustion at the lower end, substantially as specified, to insure the burning of the central part of the charge, as specified.

2. I also claim cooling the calcined lime preparatory to drawing it out, and exposing it to the atmosphere, by causing a current of cold air to pass through the saddle, or its equivalent, placed at the bottom of the stack, and on to which the calcined lime descends as described.

CLARK D. PAGE.
